UNION-PAJAMAS.

1,211,002.

Specification of Letters Patent.

Patented Jan. 2, 1917.

Application filed October 20, 1913. Serial No. 796,188.

To all whom it may concern:

Be it known that I, BURR C. STEPHENSON, a citizen of the United States, residing at South Bend, in the county of St. Joseph and 5 State of Indiana, have invented certain new and useful Improvements in Union-Pajamas of which the following is a specification.

The invention relates generally to an improvement in pajamas and particularly to a 10 garment of this character constructed to provide a union pajama, in which the respective portions of the garment, while presenting the appearance of the usual separate garments, are in fact connected to facilitate the use of the garment as a whole and 15 avoid discomfort and inconvenience usually attendant upon the garment when in independent section.

The main object of the present invention 20 is the provision of a union pajama in which upper and lower garments are connected to permit the garments having the appearance of the usual two-piece garment, the rear portion of the trousers being formed to provide 25 a detachable flap, and the garment as a whole opening when desired from the neck to the crotch portion.

The invention in its preferred form of 30 details will be described in the following specification, reference being had particularly to the accompanying drawings, in which:—

Figure 1 is a view of the garment as in 35 use, the lower part of the trouser portion being broken away. Fig. 2 is a similar view showing the front part of the coat portion raised and also showing the front opening in the trouser portion. Fig. 3 is a vertical section partly broken away illustrating particularly the rear flap construction. Fig. 4 40 is a broken rear elevation of the garment showing the depending part of the coat portion raised and the flap partly open.

The improved union pajama, as will be 45 apparent from the drawings, embodies the usual upper garment or coat 1 and the lower garment or trousers 2, and each garment, except in the specific details hereinafter noted, being of any usual or preferred construction 50 or arrangement.

The upper marginal edge 3 of the trousers portion is united to the coat portion by stitching 4, the trouser portion being secured to the inner side of the coat portion and at

some distance above the lower end of such 55 coat portion, the arrangement providing for the proper support of the trouser portion from the coat portion when the garment is in use. The coat portion is as usual, open throughout the full length of the front, 60 while the trouser portion is as usual, provided with an opening 5 in line with the front coat opening, so that by virtue of these two openings the union garment as an 65 entirety may be open from the neck to the crotch portion, permitting the convenient application or removal of the garment from the person. To facilitate the opening of the trouser portion, the connection of the upper 70 margin of the trouser portion and the coat 75 does not extend to the marginal edge of the opening 5, but terminates some distance short of said edge to thereby permit convenient handling of the material in buttoning or unbuttoning the opening.

The trouser portion throughout the rear breadth thereof is in the form of a flap 6 which of course is stitched at its upper marginal edge to the coat portion, depending therefrom to a point some distance above the 80 lower edge of the coat portion and being otherwise wholly free of connection with the coat portion. The rear portion of the pajamas coincident with that of the flap 6 is in the form of a drop seat 7, having a 85 length to extend above the lower edge of the flap 6, the edge division of the drop seat with respect to the trousers proper being such as to permit said drop seat to be folded 90 downwardly to form an opening in the garment. The upper edge of the drop seat is provided with button holes 8 and buttons 9 are approximately secured to the flap 6, permitting the drop seat to be secured in raised or elevated position with the effect to complete 95 the trousers portion of the garment. In this connection it will be obvious from the drawings that that portion of the coat beneath the line of connection between the coat and trousers will overlie and conceal 100 the drop seat, flap, and attaching means, so that the garment in use presents the ordinary appearance of the usual two-piece garment, though when constructed as described it obviates the use of the usual draw string 105 and avoids inconvenience and discomfort attendant upon the separate constructions of the respective garments.

What is claimed is:—

A pajama having a coat and trousers combined to form a one-piece garment, the trousers having a fly front, a closed crotch, 5 a slack seat, and a drop-seat flap, the openings at the sides of such seat-flap being in the body portion of the trousers and ending above the crotch, and the coat having a skirt falling over such fly front and side openings of the trousers, the back of the coat being provided, under such skirt, with an 10

attaching band for the drop seat-flap, such band being so located that it normally occupies a position on the wearer below his waist line.

In testimony whereof I affix my signature in presence of two witnesses.

BURR C. STEPHENSON.
